UNITED STATES PATENT OFFICE.

JACOB SUESS, OF CHICAGO, ILLINOIS, ASSIGNOR OF ONE-HALF TO CHARLES WOODWARD,
OF CHICAGO, ILLINOIS.

MECHANICAL LUBRICATOR.

No. 894,472.

Specification of Letters Patent.

Patented July 28, 1908.

Application filed March 9, 1907. Serial No. 361,439.

To all whom it may concern:

Be it known that I, JACOB SUESS, a citizen of the United States, residing at Chicago, in the county of Cook and State of Illinois, have 5 invented new and useful Improvements in Mechanical Lubricators, of which the following is a specification.

This invention relates to mechanical lubricators and is especially adapted for use on 10 automobiles and other high speed machines.

The object of the invention is to provide a mechanical lubricator of simple construction and few parts in which the oil is delivered in quantities as required to a plurality of feeds 15 by a single pump.

The invention has other objects in view which will appear hereinafter in a detailed description of the drawings which show one embodiment of the invention and in which 20 Figure 1 is a sectional elevation; Fig. 2 is a sectional view on the line 2—2 of Fig. 1; Fig. 3 is a detail sectional view; Figs. 4 and 5 are sectional views on the line 4—4 of Fig. 1; Fig. 6 is a detail sectional view.

25 Referring to the drawings in which like numerals of reference designate corresponding parts in the several figures, 7 is an oil reservoir of suitable size and shape within which the pump mechanism is inclosed. A drive 30 shaft 8 is journaled in a wall 7' of the reservoir and in a standard 9 within the reservoir and this shaft carries a pulley 10 outside of the reservoir and a pinion 11 within the reservoir. The pinion 11 meshes with a gear 12 arranged within the reservoir on a stub shaft 13 supported on the wall 7' of the reservoir. A disk 14 is fastened to the gear 12 and is provided with a groove 15 and a collar 16. A piston 17 is arranged to operate in the 40 pump cylinder 18 supported within the reservoir and this piston has on its upper end a rectangular frame 19 provided with inturned side flanges 20 which operate in the groove 15 (Fig. 3). The disk 15 carries a wrist pin 45 21 which operates within a frame 21' on the lower end of a plunger 22, the latter projecting upward through an opening 22' in the frame 19 and an opening 22" in the reservoir and carrying a spring 23 which is confined 50 between the top of the frame 19 and nuts 24 on the outer end of the plunger. The pump cylinder is provided with a tubular extension 25 at its lower end which has an inlet opening 26 normally closed by a ball valve

27 and a valve seat 28 at its outer end on 55 which the ball valve 29 is normally seated.

A delivery pipe 30 is connected to the outer end of the extension 25 and to a bore 31 which forms an oil distributing channel in the casing 32 and communicates independently with each of the valved feeds. Each of these valved feeds comprises an upwardly inclined passage 33 leading from the distributing channel 31 to the seat 34 of the valve 35 carried by a regulating screw 35', this seat 65 being located at the upper end of a passage 36. The screw 35' operates in a boss 37 on which a cap 38 is screwed. A plunger 39 is arranged in a chamber 40 in the valve casing 32 below the passage 36 and this 70 plunger is normally held in the position shown in Fig. 5 by a spring 41 located between the end of the plunger and an adjusting screw 42 in one end of the chamber 40. The plunger carries a rod 43 which projects 75 through an opening 44 in the valve casing and is provided with a handle 45 of any suitable character. The inner end of the plunger is provided with an angularly disposed channel 46 which receives the oil from 80 the passage 36, when the parts are in the position shown in Fig. 5 and permits it to flow therethrough into the chamber 40 and thence to the nipple 47 whence it is carried to the parts to be lubricated. The plunger is also 85 provided with a bleeder groove 48 which forms a communication, when the parts are in the position shown in Fig. 4 between the passage 36 and a passage 49 in the valve casing below the chamber 40 and discharging 90 through a sight chamber 50 and an opening 51 into the reservoir. The sight chamber is located in the part which has been generally referred to as the valve casing and beneath the plunger 39 and it is provided with a 95 glass front 52. It will be understood that all of the feeds are similarly provided with the parts hereinbefore described and illustrated in Figs. 4 and 5 and that the apparatus may be equipped with as many of these 100 feeds as desired.

The operation may be briefly described as follows:—Assuming first that it is desired to regulate the feed, the pump is started in operation and the plunger 39 is pushed inward 105 until the bleeder groove 48 is aligned with the passages 36 and 49. The oil will flow through the pipe 30, the distributing channel 31 into

the passage 33 and passage 34 through the groove 48 and passage 49 and drip through the sight chamber 50 and opening 51 back into the reservoir. By observing the drops 5 through the glass 52 and adjusting the screw 35' the feed can be regulated as required and in this connection it will be observed that each feed is separately regulated and therefore that the flow of oil in the several feeds 10 may be the same or different as desired. Then pressure on the plunger is released to permit the spring 41 to return the plunger to its normal position, as shown in Fig. 5, whereupon the oil flows from passage 36 15 through channel 46 and chamber 40 to the feed nipple 47. To operate the pump power is applied to the shaft 8 whereby the gear 12 and disk 14 are revolved. The wrist pin reciprocates the plunger 22 and the pressure 20 of the spring 23 operates the piston 17. The wrist pin operating in the frame 21' reciprocates the plunger 22 and on the upward stroke of the plunger the frame 21' engages the frame 19 to raise the piston 17. When 25 the wrist pin proceeds on its downward stroke carrying with it the plunger, the spring 22'' is compressed by the resistance of the piston and by expansion operates the piston in a downward direction. The pump sucks 30 in the oil from the reservoir through opening 26, unseating ball valve 27, and forces the oil from the cylinder 18 into delivery pipe 30 by unseating the ball valve 29, the ball valve 27 being seated during the de- 35 livery stroke of the pump. The supply of oil delivered by the pump is regulated by spring 23 to avoid exceeding the amount of oil required because the spring will not operate the piston when the back pressure on 40 the piston is greater than the expansive pressure of the spring.

As the passages 33 leading from the distributing channel to the valve seats 34 are inclined upwardly the oil will be prevented 45 from wasting when the pump is not in operation. The nuts 24 on the plunger 22 can be adjusted as required to provide the proper pressure for operating the pump piston.

What I claim and desire to secure by Letters Patent is:

1. In a mechanical lubricator, the combination of a reservoir, a plurality of feeds, and a pump for supplying oil from the reservoir to the feeds, said pump comprising a cylinder having an oil inlet and outlet, a piston operating in the cylinder, a plunger, a spring carried by the plunger and bearing on the piston, and means for compressing said spring to operate the piston in a downward direction.

2. In a mechanical lubricator, the combination of a reservoir, a plurality of feeds, and a pump for supplying oil from the reservoir to the feeds, said pump comprising a cylinder having an oil inlet and outlet, a piston op-

erating in the cylinder, a plunger, an adjustable stop on said plunger, a spring confined between said stop and the upper end of the piston, and means for operating the plunger to compress the spring to operate the piston in a downward direction.

3. In a mechanical lubricator, the combination of a reservoir, a plurality of feeds, and a pump for supplying oil from the reservoir to the feeds, said pump comprising a cylinder having an oil inlet and outlet, a piston operating in the cylinder, a plunger, an adjustable stop on the plunger, a spring arranged on the plunger between said stop and the upper end of the piston, a driven gear, and a wrist pin carried by said gear and operating the plunger to compress the spring to operate the piston in a downward direction.

4. In a mechanical lubricator, the combination of a reservoir, a plurality of feeds, and a pump for supplying oil from the reservoir to the feeds, said pump comprising a cylinder having an oil inlet and outlet, a piston operating in the cylinder, a plunger, a spring on the plunger to operate the piston in a downward direction, a driven gear, a disk rigid with said gear, a frame on the piston and guided on said disk, a frame on the plunger arranged within the piston frame, and a wrist pin on the disk operating in the plunger frame to raise the plunger and compress the spring.

5. In a mechanical lubricator, the combination of a reservoir, a plurality of feeds, and a pump for supplying oil from the reservoir to the feeds, said pump comprising a cylinder having an oil inlet and outlet, a piston operating in the cylinder, a driven gear, a disk rigid with said gear and provided with a guide groove, a frame on the piston, and having flanges to operate in said groove, and a wrist pin on the disk and operating in said frame.

6. In a mechanical lubricator, the combination of a reservoir, a plurality of feeds, and a pump for supplying oil from the reservoir to the feeds, said pump comprising a cylinder having an oil inlet and outlet, a piston operating in the cylinder, a driven gear, a disk rigid with said gear and provided with a guide groove, a frame carried by the piston, and having flanges operating in said guide groove, a plunger, an adjustable stop on said plunger, a spring on the plunger between said stop and said frame, and a wrist pin on the disk for operating the plunger to compress the spring to operate the piston in a downward direction.

7. In a mechanical lubricator, the combination of a reservoir, a casing on the reservoir having a channel bore therein, a pump for supplying oil from the reservoir to said channel bore, said casing having a plurality of sight feeds each comprising a valve seat,

an adjustable valve, a passage leading from the channel bore to said seat, a passage leading from said seat, a nipple, a chamber communicating with said passage leading from the seat and said nipple and through which the oil passes to the nipple, and a bleeder valve in said chamber.

8. In a mechanical lubricator, the combination of a reservoir, a casing on the reservoir having a channel bore therein, a pump for supplying oil from the reservoir to said channel bore, said casing having a plurality of sight feeds each comprising a valve seat, an adjustable valve, a passage leading from the channel bore to said seat and inclined upwardly from the channel bore to the seat, a passage leading from said seat, a nipple, a chamber communicating with said passage leading from the seat and said nipple and through which the oil passes to the nipple, and a bleeder valve in said chamber.

9. In a mechanical lubricator, the combination of a reservoir, a casing on the reservoir provided with a channel, a pump for

supplying oil from the reservoir to said channel, there being a valve seat in said casing and a passage leading from the channel to said seat, an adjustable valve, there being a nipple on the casing and a chamber below the valve seat communicating with said nipple, a spring-pressed plunger in said chamber and having a bleeder groove, said casing having a passage leading from the seat to said chamber to permit the flow of oil therethrough into the chamber when said plunger is in normal position, said bleeder groove being adapted to be brought into alignment with the passage connecting the seat and chamber, there being a sight chamber in the casing below the plunger chamber and a passage leading from said plunger chamber to the sight chamber and a communication between the sight chamber and reservoir.

JACOB SUESS.
